UNITED STATES PATENT OFFICE.

DANIEL LOCKE, OF SUMMERFIELD, KANSAS.

TENSION DEVICE.

1,303,486.

Specification of Letters Patent. Patented May 13, 1919.

Application filed December 14, 1918. Serial No. 266,828.

To all whom it may concern:

Be it known that I, DANIEL LOCKE, a citizen of the United States, residing at Summerfield, in the county of Marshall and State 5 of Kansas, have invented certain new and useful Improvements in Tension Devices, of which the following is a specification.

The object of this invention is to provide simple and efficient means for maintaining 10 a line under tension and automatically returning the same to its normal position after an abnormal strain has been placed thereon. The invention is illustrated in the accompanying drawings and will be herein- 15 after first fully described and then more particularly pointed out in the appended claims.

In the said drawings—

Figure 1 is an elevation showing my im- 20 proved device applied to a horizontally swinging gate;

Fig. 2 is a plan view of the tension device illustrated in Fig. 1;

Fig. 3 is a horizontal section on the line 25 3—3 of Fig. 2;

Figs. 4 and 5 are transverse sections taken respectively on the lines 4—4 and 5—5 of Fig. 3;

Fig. 6 is an elevation showing the device 30 applied to a fence wire;

Fig. 7 is a detail section on the line 7—7 of Fig. 6.

In the application of my invention to a 35 swinging gate to prevent sagging of the same, I employ a base which is secured to the upper end of the gate post 1 and is illustrated as consisting of a central plate 2 extending over the upper end of the post and provided at its side edges with pendent lugs 40 or ears 3 having perforations 4 near their lower ends through which fastening devices 5 are inserted into the post to secure the said base in position. At the center of the main plate 1 is an opening in which is swiv- 45

eled the stem 6 of a fork 7 and at the upper end of said fork, between the tines of the same, I fulcrum, as at 8, a tension lever, the fulcrum 8 being eccentric to the arm 9 of the lever. The lever may be conveniently formed 50 of sheet metal having its long arm or main portion rolled into tubular form, as shown at 10, and having its edges brought together to provide a reinforcing longitudinal rib 11, as shown most clearly in Fig. 5. The fulcrum end of the lever is laterally or eccentrically enlarged and consists of parallel 55

wings 12 extending from the end of the tubular portion 10. Between the wings 12 and at the edge more remote from the fulcrum 8, I mount guiding and tension rollers 60 13 over which the tension or guy wire 14 is trained and upon the outer side of the arm 9 of the lever I provide a hook or stud 15 over and around which the end of the said wire may be engaged, the extremity of the 65 wire being doubled upon itself to engage said stud and being secured to the main strand of the wire by a clamp 16 of any preferred construction. The free end of the wire is attached to the upper bar of the gate 70 17, as shown at 18, and a retaining loop 19 may be secured upon the gate bar and passed over the wire, as clearly shown in Fig. 1. In the upper edge of the arm 9 of the lever, I provide a longitudinal series of 75 transverse notches 20, in any one of which may be engaged the loop 21 at the upper end of a counterbalance weight 22, it being readily understood that the loop will be engaged in one or another of said notches ac- 80 cordingly as it may be desired to have the weight closer to the fulcrum or more remote therefrom and thereby vary the effective length of the lever and, consequently, regulate the tension as may be desirable. 85

The gate hinges are preferably of that type which employ a pin 23 on the post and an eye 24 on the gate encircling said pin. To prevent the gate rising from the hinges, I mount upon the post above either hinge a 90 locking cam 25 which is pivoted upon the post and tends normally to gravitate into a position directly over the hinge eye so that any upward movement of said eye will be resisted by the latch or locking cam but if 95 it be desired to remove the gate for repairs or other purposes the disengagement of the hinge members can be easily effected by merely swinging the said latch about its pivot or fulcrum so that it will clear the 100 hinge.

It is thought to be clear from the foregoing description, taken in connection with the accompanying drawings, that the use of the device shown and described will effec- 105 tually prevent sagging of the gate inasmuch as the tension or guy wire 14 is attached to the top of the gate near the free or swinging end thereof and any tendency of the gate to sag will, consequently, increase the 110 tension to which the said wire is subjected. The weight 22 will be adjusted upon the ten-

sion lever so that it constantly resists the effort of the lever to swing toward and over the gate under the strain placed thereon by the weight of the gate so that the gate will 5 remain plumb throughout its life. It will also be readily noted that the lever is mounted upon a swiveled fulcrum so that it will readily follow the turning movement of the gate and will not interfere in any degree 10 with the opening or closing movement.

In Figs. 6 and 7, I show how the tension lever and the parts coöperating therewith may be applied to a fence wire without any material change in construction. In this embodiment of the invention, the swiveled support for the lever is dispensed with and a bracket consisting of a substantially U-shaped body portion 30 and a lateral tongue 31 extending from one side of said body portion 15 is employed, the tongue 31 being secured to the side of the post so that the parallel side members of the U-shaped body portion will be substantially parallel with the line of the fence. A roller 32 is mounted upon the fulcrum pin of the lever 33 and this fulcrum pin 34 is inserted through the post 35 and through the end of the U-shaped body portion 30 so that the roller will be disposed between the post and the extremity of said 20 body portion, as clearly shown in Fig. 7. A tension roller 36 is mounted between the side wings 37 of the lever at the edge more remote from the fulcrum and the fence wire 38 is carried under the roller 32 and then over the said roller 36 to be engaged over and around the hook or stud 39 on the upper side of the tension lever. The weight 40 is hung upon the arm of the lever in the same manner as the weight 22 is hung upon the lever 25 in the form previously described. It will be understood, of course, that the lever extends over the fence wire and along the line of the fence away from the post so that the action of the weight 40 is to maintain the fence wire under tension at all times. Should live 30 stock run against the fence or from any other cause the fence wire should be subjected to an abnormal strain, the force of the counterbalance weight will be temporarily overcome so that the wire will be slackened somewhat and will be thereby prevented from 35 breaking but the instant the abnormal strain is removed the weight returns the parts to the initial or normal position, swinging the lever about its fulcrum and thereby causing the tension roller 36 to swing upwardly away from the line of the tension wire and causing the hook 39 to swing rearwardly so that a pull will be exerted upon the wire and it will 40 be held taut.

It will be noted that in both applications of the invention the upper web or top of the arm 9 of the lever is provided with an inclined or beveled member 41 between the 45 wire-holding stud or hook and the tension

roller so that the tension wire will not be subjected to a cutting action by the end of said web. It will also be noted that in applying the device to a gate the bracing or tension wire is trained under the outermost 70 tension roller and over the inner tension roller so that the tendency of the lever to swing downwardly under the action of the counterbalance weight will pull upon the wire and keep the same taut. 75

The device is exceedingly simple in the construction and arrangement of its parts and may be readily applied to any gate or fence. It is to be understood, however, that the utility of the device is not limited to 80 fences as it may be applied to clothes lines and to other places where it is desired to maintain a line of rope or cable under tension and in a taut condition.

Having thus described my invention, what 85 is claimed as new is:

1. A device for the purpose set forth comprising a lever consisting of an arm and parallel wings extending from one end of said arm, the end of the arm adjacent the 90 wings being beveled, a stud on the upper side of the arm adjacent said beveled end, a fulcrum inserted through said wings eccentric to the arm, a line-engaging tension member carried by said wings, and a counterbalance suspended on the arm. 95

2. A device for the purpose set forth comprising a lever consisting of an arm and spaced wings extending from one end of said arm, a line-securing device on the upper side of the arm, a fulcrum inserted through said wings eccentric to the arm, a line-engaging tension member carried by said wings, and a counterbalance suspended 100 from the arm. 105

3. A device for the purpose set forth comprising a lever consisting of a swinging arm and spaced wings extending from one end of said arm, a fulcrum inserted through said wings eccentric to the arm, a line-engaging tension device interposed between said wings and arranged eccentric to the fulcrum of the lever, a line-securing device on the arm at the end thereof adjacent the wings, and a counterbalance suspended from 110 the arm. 115

4. A device for the purpose set forth comprising a lever consisting of a swinging arm and spaced wings extending from one end of said arm, the upper longitudinal edge of 120 the arm being provided with spaced notches, a fulcrum inserted through said wings eccentric to the arm, a line-engaging tension device interposed between said wings and arranged eccentric to the fulcrum of the lever, a line-securing device on the arm at the end thereof adjacent the wings, and a counterbalance suspended from the arm and including a loop adapted to fit within the notches 125 in the lever. 130

5. A device for the purpose set forth comprising a supporting base, a forked stem swiveled on the base, a lever having spaced wings extending from one end thereof and fitting within the forked end of the stem, a fulcrum inserted through said wings and forked end of the stem and arranged eccentric to the arm, a line-engaging tension device interposed between said wings and arranged eccentric to the fulcrum of the lever, 10 a line-securing device on the arm at the end thereof adjacent the wings, and a counterbalance suspended from the arm.

In testimony whereof I affix my signature.

DANIEL LOCKE. [L. S.]
